UNITED STATES PATENT OFFICE.

EDWARD C. HOCK, OF BUFFALO, NEW YORK.

SMOKE-CONSUMING HEATER OR BOILER.

1,097,718.

Specification of Letters Patent. Patented May 26, 1914.

Application filed October 1, 1913. Serial No. 792,793.

To all whom it may concern:

Be it known that I, EDWARD C. HOCK, a citizen of the United States, residing at Buffalo, in the county of Erie and State of New York, have invented certain new and useful Improvements in Smoke-Consuming Heaters or Boilers, of which the following is a specification.

My invention relates to smoke consuming heaters or boilers, and it has for its primary object the provision of a sectional heater or boiler capable of being enlarged or diminished in size by increasing or diminishing the number of sections and in which the smoke consuming portion of the heater or boiler is cast integrally therewith, said smoke consuming portion being likewise constructed in sections and adapted to have the sections connected in like manner to the heater or boiler sections.

Another object of my invention is the provision of means for drawing hot air into the passage receiving the outer air, which hot air thoroughly mixes with the outer air and thus insures a quick heating of said outer air in its course of travel to the fireplace.

Other objects are to provide a smoke consuming heater or boiler of the sectional type in which the smoke consuming portion thereof is cast in sections integral with the heater or boiler sections, and to otherwise improve on smoke consuming heaters and boilers now in use.

To these ends the invention consists in equipping a sectional heater or boiler with an air passage or passages, said air passage or passages being formed in sections corresponding to the boiler sections and integral therewith.

It further consists in the provision of means for introducing hot air into a passage or passages from the fireplace so as to commingle with the exterior air drawn into said passage or passages, for the purpose of more readily heating the exterior air in its course of travel into the fireplace.

It further consists in the novel features of construction, and in the arrangement and combination of parts to be hereinafter described and more particularly pointed out in the subjoined claims.

In the drawings.—Figure 1 is a sectional perspective view of a sectional heater or boiler embodying my invention in one of its representative forms. Fig. 2 is an enlarged

horizontal section taken on line *a—a*, Fig. 1. Fig. 3 is an enlarged horizontal section taken on line *b—b*, Fig. 1. Fig. 4 is an enlarged transverse section taken on line *c—c*, Fig. 2. Fig. 5 is an enlarged vertical section taken on line *d—d*, Fig. 3. Fig. 6 is a horizontal section of a modified form of my invention taken on plane passing through a heater or boiler indicated by line *a—a*, Fig. 1.

While the above described figures illustrate the nature of my invention and the manner of applying the same to a sectional water heater or boiler of a particular type, it is fully within the province of my invention to apply the same to any other form of sectional heater, boiler or furnace in which the consumption of smoke and unconsumed gases is desirable, and it is to be understood that the construction illustrated is merely the preferred embodiment of my invention for the particular type of boiler or heater shown.

Referring now to the drawings in detail, like numerals of reference refer to like parts in the several figures.

The reference numeral 12 designates the front section, 13 the rear section, and 14 the intermediate sections of the heater or boiler, said heater or boiler being of the sectional type of which there are many now in use, the particular construction of the several sections being immaterial to the application of my invention thereto. The sections of heaters or boilers of this type are usually connected by means of nipples, and provision is made for the passage of the heat through the assembled boiler sections so as to heat or boil the water therein, all of which is unimportant to my present invention.

When the sections of the heater or boiler are assembled, a fireplace 15 is provided beneath which is the usual ash pit 16 separated from the fireplace by the fuel grate 17. The rear section 13 of the heater or boiler has cast integrally therewith and on the inner face thereof a conduit 18 which extends from one vertical edge of the said section to the other, and spaced from said conduit 18 is a second conduit 19 formed in two spaced sections 20, 21, the space separating said sections being at the center of the rear boiler section. From this space the two sections extend in opposite directions coextensive with the conduit 18 to the opposite ver-

tical edges of the rear boiler section. Passing through the rear section centrally of said space is an opening 22 and extending through said opening from the inside of the 5 boiler section is one arm of a T-shaped fitting 23, the other portion or head of said fitting occupying the space between the two spaced sections of the conduit 19. Said fitting is made hollow and serves to introduce air 10 into the two spaced sections of the conduit 19 and in order to cause the heated air from the fireplace to be drawn into said conduit the T-shaped fitting has openings 24 facing downwardly and also nozzles 25 threaded or 15 otherwise secured thereto which are arranged in operative relation to said openings 24. The air entering from the exterior through said T-shaped fitting passes through the nozzles and has a tendency to draw the 20 hot air from the fireplace into the conduit 19 through the openings 24 at the bottom of said T-shaped fitting.

The front section of the heater or boiler is provided with the usual openings for introducing fuel into the fireplace, for providing access to the ash pit, and for cleaning or otherwise attending to other portions of the heater or boiler. The intermediate sections of the heater or boiler have side 30 legs 26 at opposite sides of the fireplace and on the inner face of each leg is cast a conduit 27 which is arranged in line with the conduit 18 on the inner wall of the rear section and spaced from each of said conduits on the legs of the said sections is cast another conduit 28 in line with the conduit 19 on the inner face of said rear section. The conduits of adjoining sections are connected together by push nipples 29, said 40 nipples being similar to those usually employed in connecting the sections of the heater or boiler together. The foremost section having the conduits thereon are provided at each side of the fireplace with a U-shaped connector 30; said connectors having reduced ends 31 which enter the conduits and being held in place by set screws 32, or otherwise. These U-shaped connectors connect the upper and lower conduits together. 45 By thus constructing the conduits and connecting the same, two passages are provided which extend from a point near the front of one side wall rearwardly and around the rear wall to a similar point of the other side wall. The conduits forming one of the passages having air escape apertures 33.

In the construction described, the exterior air is drawn into the passages through the T-fitting 23 and in passing through the nozzles in said fittings, creates suction to draw into said passage the hot air from the fireplace. The hot air and exterior air therefore commingle in their course through the imperforate passage and pass forwardly 60 along both sides of the heater or boiler, be-

ing heated by the impinging flames of the fuel in the fireplace. The air thus thoroughly heated then passes through the U-shaped connectors and enters the perforated passage, from which it escapes through the perforations thereof and in passing out into the fireplace causes the unconsumed products of combustion to be ignited. This greatly increases the heating capacity of the boiler and tends to save considerable fuel.

In the preferred embodiment of my invention described, the air passages are arranged so that an imperforate portion and a perforated portion are provided, the imperforate portion being adapted to be subjected to the heat of the fireplace so as to thoroughly heat the air passing therethrough preparatory to passing into the perforated portion and escaping therefrom. This is accomplished by extending the passages in spaced relation and connecting them at two points so as to make them substantially endless, introducing air at one point and allowing it to escape through a plurality of perforations, for the purpose described.

For the purpose of referring to the air passages disclosed in my invention by a generic term, I will refer to them as "tubes" in the claims, by which term I intend to include all constructions, in which air passages are formed.

Having thus described my invention, what I claim is,—

1. In a sectional heater or boiler, the combination with a fireplace having a tube on the wall thereof formed in sections co-extensive with the heater or boiler sections, the sections of said tubes being joined together in corresponding relation to the sections of the heater or boiler and having an inlet for the admission of exterior air and perforations for the escape of the air therefrom when heated, for the purpose set forth.

2. In a sectional heater or boiler, the combination with the fireplace, of an air tube cast integrally with the wall or walls of said fireplace, said tube being formed in sections on a plurality of the heater or boiler sections and the tubes on adjoining heater or boiler sections being connected to form a connected passage, said passage having an inlet for the admission of exterior air, an imperforate portion into which the exterior air passes to be heated from the heat in the fireplace and perforations for the escape of the heated air passing through said imperforate portions, for the purpose set forth.

3. A sectional heater or boiler having a rear section, a front section, and intermediate sections connected together, tubes cast integrally with the side walls of said intermediate sections and arranged in two planes, the tubes in each plane being joined together to form two passages, means for connecting said passages, means for admitting hot air

to one of said passages, means for admitting exterior air to said last-mentioned passage so as to commingle with the hot air admitted thereto and be heated in passing there-
5 through, and means allowing the escape of air into the fireplace from the other passage after being heated, for the purpose set forth.

4. A smoke consuming heater or boiler formed of connected sections, each section 10 having spaced tubes cast integral therewith with the tubes of the several sections suitably connected, one of said tubes having connection with the outer air and another having openings for the escape of the air into 15 the fireplace, for the purpose set forth.

5. A smoke consuming heater or boiler formed in sections and having two spaced air passages in each section, means for connecting the air passages of adjoining sections, means for connecting the air passages of one of said sections, and means of connection between one of the air passages of one section with the exterior air, one air 20 passage of each section having perforations 25 to permit the escape of air therefrom into the fireplace, for the purpose set forth.

6. A sectional heater or boiler comprising a rear section, a front section and intermediate sections, said sections being joined 30 together, said rear section having a per-

forated passage with the perforations facing inwardly from said passage, and two imperforate passages spaced apart, said rear section having also an opening extending from its inner face to its outer face, a T-fitting 35 entered in said opening and connecting said two imperforate air passages, said fitting having oppositely-disposed nozzles therein and openings for admission of hot air thereto, one opening being in operative relation to each nozzle, the opposite walls of the intermediate sections having two air 40 passages, one passage of each wall being perforated and the other imperforate, the passages of the intermediate sections being 45 joined together and with the passages of the rear section so as to provide a perforated passage extending across the rear wall of the fireplace and thence forwardly therefrom, and an imperforate passage connected 50 to the forward ends of said perforated passage and extending rearwardly therefrom and across the rear section to said T-fitting, for the purpose set forth.

In testimony whereof I affix my signature 55 in presence of two witnesses.

EDWARD C. HOCK.
